BOOT HOLDER OR SIMILAR ARTICLE

Leon W. Hammer, Ogden, Utah
(Rte. 2, Weiser, Idaho 83672)

Filed Mar. 10, 1970, Ser. No. 21,841

Term of patent 3½ years

Int. Cl. D6—99

U.S. Cl. D6—116

FIG. 1 is a perspective view of a boot holder or similar article showing my new design; and

FIG. 2 is a side elevation of the invention shown in FIG. 1.

I claim:

The ornamental design for a boot holder or similar article, as shown.
